HEDDLE MECHANISM FOR CIRCULAR LOOMS

Victor Marie Joseph Ancet, Lyon, France,
assignor to Regina S. A., Tangiers, MoroccoApplication August 1, 1947, Serial No. 765,560
In France November 30, 1945Section 1, Public Law 690, August 8, 1946
Patent expires November 30, 1965

5 Claims. (Cl. 139—16)

1

This invention relates to heddle mechanism for use in circular looms and is concerned more particularly with a novel heddle mechanism for use in such looms, which is of simple construction and in which the heddle wires are supported for independent relative movement and can be readily removed and replaced.

The new mechanism includes an annular support mounted concentrically with the loom shaft and having horizontal radial guideways in two groups in upper and lower levels. A slide having a blade at its outer end is mounted for endwise movement in each guideway and the blades on adjacent slides in the same level carry elements, such as rods or strips, extending through openings in the blades and having enlarged heads or like means for preventing their displacement. Each blade has upper and lower openings near each end and is connected to the blade on one side by elements in the upper openings and to the blade on the other side by elements in the lower openings. Heddle wires lie in each space between adjacent blades and have loops at their ends, through which pass the elements crossing the space and connecting the blades at opposite sides thereof. The slides in the two levels are moved radially by suitable cam means and a reed of annular form and in two or more sections is mounted on the annular support to overlie the slides.

For a better understanding of the invention, reference may be had to the accompanying drawings, in which

Fig. 1 is a view partly in elevation and partly in vertical section of one form of heddle mechanism of the invention;

Fig. 2 is a sectional view on the line 2—2 of Fig. 1, with parts removed; and

Figs. 3 and 4 are fragmentary perspective views showing two forms of heddle wire mountings.

The loom, of which a part is shown in the drawings, includes a vertical drive shaft 10, which extends through the central opening of an annular support 11 carried by legs 12. The support has a peripheral flange 11a, on which are mounted a plurality of guide blocks 13 arranged at uniform spacings in a circular series. Each block is provided with a transverse curved rib 14 on its under surface, which is receivable in a corresponding groove in the upper face of the flange 11a of the support, and the blocks are held in position by bolts 15 passing through openings in flange 11a and into the blocks. Each block has vertically aligned upper and lower radial guide-

2

ways, in each of which is mounted a slide 16 having a blade 17 attached to its outer end and extending outwardly in prolongation thereof.

Each blade has upper and lower openings 18 near each end and each blade is connected to the blade on one side thereof by a pair of elements passing through the upper openings in the two blades and to the blade on other side thereof by elements passing through the lower openings in the two blades. The elements may be rods 19 (Fig. 3), each of which is provided with an integral enlarged head 20 at one end and a removable cap 21 at the other end, or the elements may be flat strips 22 preferably of metal, each strip having an enlarged head 23 at one end and a spring locking member 24 at the other end. If the elements are of rod form, the openings 18 in the blades are circular whereas, if strips are employed, the openings 18a through the blades are elongated lengthwise of the blades, so that the strips lie with their wide faces horizontal. By removal of the cap 21 from a rod 19, the rod may be withdrawn from the openings in the blades, in which it is mounted. Similarly, the locking member 24 on a strip 22 may be depressed, so that the end of the strip carrying the member may be passed through the openings in the blades.

The elements extending across the space between adjacent blades in either the upper or lower series are connected by heddle wires 25, each of which has a loop 26 at each end, through which the rods 19 or strips 22 may be passed, and the usual eye 27 between its ends. The heddle wires are loosely strung on the rods, so that they are independently movable and may assume their proper relative positions.

In the operation of the loom, the warp threads 28 are formed into a shed, through which the shuttle passes, by inward radial movement of the successive slides in one level and outward radial movement of the corresponding slides in the other level. The radial movement of the slides is effected by cam means and, for this purpose, a cam 29 may be mounted on shaft 10 above the annular support 11, the cam having a groove 29a, in which run the rollers 30 on the inner ends of the slides in the lower level. Corresponding slides in the two levels are provided with rack teeth 31, 32 on their opposed faces and each guide block 13 is formed with a central opening 33 between the guideways and containing a pinion 34 mounted for free rotation and meshing with the teeth 31, 32 on the respective slides. With this arrangement, as the lower slide 16 is moved

outwardly, for example, by the action of the cam on its roller, its rack teeth cause rotation of pinion 34 and this, in turn results in inward movement of the corresponding upper slide 16.

An annular member 35 is mounted on top of the series of guide blocks and projects outwardly therefrom. The member 35 carries a reed 36 of annular form, the reed overlying the blades 17 and lying parallel thereto. The reed is preferably made in a plurality of sections and the member 35 is formed with a peripheral rim 35a having a slot in its outer face, in which the inner edge of the reed is received to be held in place by a plurality of set screws 37.

With the construction described, the heddle wires in each group carried on a pair of elements spanning the space between adjacent blades are freely movable relative to one another, since the portions of the elements lying between opposed faces of the blades are of uniform size from end to end. There are thus no obstructions on the elements, which would interfere with the free movement of the wires as they adjust themselves to their proper relative positions. Should a single wire become broken or defective and require replacement, the elements, on which the wire is mounted, need be removed from only one of the blades in which they are supported. The wires may then be slipped off the free ends of the elements until the broken or defective wire has been removed, such warp threads as are necessary being broken prior to the removal of the wires. After the defective wire has been replaced and the warp threads again passed through the eyes of their respective wires and tied up, the elements on which the group of wires are mounted may be quickly restored to their normal positions in their supporting blades. The replacement of a slide or a guide block is equally simple. The mounting of the reed in the annular member resting on and secured to the lower series of guide blocks insures that the reed will be properly positioned and held securely in place during loom operation.

What I claim is:

1. In a heddle mechanism for use in a circular loom, the combination of two circular series of slides, an annular support having horizontal radial guideways in which the slides are mounted for endwise movement, the guideways being arranged in two groups in upper and lower levels, a blade mounted at the outer end of each slide and extending outwardly therefrom, each blade having upper and lower openings near each end, elements connecting adjacent blades only of the same group and extending freely through corresponding openings in said blades, each blade being connected at both ends to the adjacent blade at one side thereof by elements in the upper openings in said blades and to the adjacent blade at the other side thereof by elements in the lower openings in said blades, each element having means at each end for engaging the blades to prevent dislodgment of the element, the means at one end being manipulable to permit the element to pass through the openings, in which it is mounted, a plurality of heddle wires in each space between adjacent blades, each wire having loops at its ends loosely encircling the elements connecting said blades, and cam means disposed centrally relative to the series of slides and operable on the slides to reciprocate them.

2. In a heddle mechanism for use in a circular loom, the combination of two circular series of slides, an annular support having horizontal

radial guideways in which the slides are mounted for endwise movement, the guideways being arranged in two groups in upper and lower levels, a blade mounted at the outer end of each slide and extending outwardly therefrom, each blade having upper and lower openings near each end, rods connecting adjacent blades only of the same group and extending freely through corresponding openings in said blades, each blade being connected at both ends to the adjacent blade at one side thereof by rods in the upper openings in said blades and to the adjacent blade at the other side thereof by rods in the lower openings in said blades, each rod having enlarged heads at its ends to prevent dislodgment of the rod, the head at one end being removable to permit the rod to be withdrawn from the openings, in which it is mounted, a plurality of heddle wires in each space between adjacent blades, each wire having loops at its ends loosely encircling the rods connecting said blades, and cam means disposed centrally relative to the series of slides and operable on the sides to reciprocate them.

3. In a heddle mechanism for use in a circular loom, the combination of two circular series of slides, an annular support having horizontal radial guideways in which the slides are mounted for endwise movement, the guideways being arranged in two groups in upper and lower levels, a blade mounted at the outer end of each slide and extending outwardly therefrom, each blade having upper and lower openings near each end, metal strips connecting adjacent blades only of the same group and extending freely through corresponding openings in said blades, each blade being connected at both ends to the adjacent blade at one side thereof by strips in the upper openings in said blades and to the adjacent blade at the other side thereof by strips in the lower openings in said blades, each strip lying with its wide faces horizontal and having an enlarged head at one end and a stop at the other to prevent dislodgment of the strip, the stop being manipulable to permit the end of the strip carrying the stop to pass through the openings, a plurality of heddle wires in each space between adjacent blades, each wire having loops at its ends loosely encircling the strips connecting said blades, and cam means disposed centrally relative to the series of slides and operable on the slides to reciprocate them.

4. In a heddle mechanism for use in a circular loom, the combination of two circular series of slides, an annular support having horizontal radial guideways in which the slides are mounted for endwise movement, the guideways being arranged in two groups in upper and lower levels, a blade mounted at the outer end of each slide and extending outwardly therefrom, each blade having upper and lower openings near each end, elements connecting adjacent blades only of the same group and extending freely through corresponding openings in said blades, each blade being connected at both ends to the adjacent blade at one side thereof by elements in the upper openings in said blades and to the adjacent blade at the other side thereof by elements in the lower openings in said blades, each element having means at each end for engaging the blades to prevent dislodgment of the element, the means at one end being manipulable to permit the element to pass through the openings, in which it is mounted, a plurality of heddle wires in each space between adjacent blades, each wire having loops at its ends loosely encircling the elements

connecting said blades, cam means disposed centrally relative to the series of slides and operable on the slides to reciprocate them, and a reed of annular form mounted on the support to overlie the blades on the slides.

5. In a heddle mechanism for use in a circular loom, the combination of an annular support, a plurality of guide blocks mounted at uniform spacings on the support, each block having upper and lower radial guideways, a slide mounted for endwise movement in each guideway, a blade mounted at the outer end of each slide and extending outwardly therefrom, each blade having upper and lower openings near each end, elements connecting adjacent blades of slides in the same level and extending freely through corresponding openings in said blades, each blade being connected at both ends to the adjacent blade at one side thereof by elements in the upper openings in said blades and to the adjacent blade at the other side thereof by elements in the lower openings in said blades, each element having means at each end for engaging the blades to prevent dislodgment of the element, the means at one end being

manipulable to permit the element to pass through the openings, in which it is mounted, a plurality of heddle wires in each space between adjacent blades, each wire having loops at its ends loosely encircling the elements connecting said blades, and cam means disposed centrally relative to the series of slides and operable on the slides to reciprocate them.
